UNITED STATES PATENT OFFICE.

JAMES D. MONIE, OF SCRANTON, PENNSYLVANIA.

MANHOLE CASING.

Application filed May 28, 1928. Serial No. 281,110.

This invention relates to the construction of manholes for sewers, vaults, water conduits, etc.

Where sewers or similar underground conduits unite it is usual at desirable intervals to construct openings leading from such conduits to the street level to afford access to the conduits. Manholes are usually constructed of brick, and usually directly over the conduit in the general form of a truncated cone.

The construction of these old manholes is time consuming and expensive, as it necessarily involves the use of expensive labor and materials, and prolonged obstruction of street traffic because of the excavation necessary to provide for the building of the manhole.

The main object of the present invention is to provide a manhole constructed in sections which can be manufactured by cheap labor away from the site of the proposed manhole and which can be very quickly assembled by cheap labor in the manhole excavation.

Another object of the invention resides in forming the manhole sections so that they can be integrally united at their joints, and thereby produce a manhole integral from top to bottom when located in sites.

Another object of the invention is to provide each section with one or more rungs which form a ladder for the manhole when the sections are assembled.

Other objects of the invention will appear as the detailed description thereof proceeds.

In the drawings:

Figure 1 is a central vertical section through a manhole of the truncated cone type;

Figure 2 is a horizontal section taken on the line 2-2 of Figure 1;

Figure 3 is an exploded perspective view, to a smaller scale, of the manhole sections shown assembled in Figure 1;

Figure 4 is a central vertical section through a cylindrical manhole taken on line 4-4 of Figure 5;

Figure 5 is a plan of the manhole shown in Figure 4, but with the trap door removed;

Figure 6 is a perspective view of the bottom section of the manhole shown in Figures 4 and 5;

Figure 7 is a central vertical section of a modified form of cylindrical manhole, taken on line 7-7 of Figure 8;

Figure 8 is a horizontal section taken on line 8-8 of Figure 7;

Figure 9 is a plan view of a further modified form of manhole made up of rectangular sections adapted to be joined end to end and laterally to form chambers of any desired size, the manhole cover being partly broken away to show details of construction;

Figure 10 is a vertical section taken on line 10-10 of Figure 9; and

Figure 11 is a vertical section through one of the units taken on line 11-11 of Figure 10.

In the form shown in Figures 1, 2 and 3 of the drawing, the manhole is of the truncated cone type, and comprises a bottom section 1 seated on a flat bed of concrete 2 and having apertures 3 and 4 through the sides thereof to receive the ends of pipes 5 and 6.

The bottom section is preferably cylindrical, while the superposed sections 7 and 8 are shaped as hollow truncated cones. The section 1 comprises an inner cylindrical plate 9 concentrically arranged within and spaced apart from an outer cylindrical plate 10, the space between the plates 9 and 10 being filled with pitch or concrete or any other suitable binding material, 11.

The upper end of the plate 9 is slightly offset inwardly to form an offset bearing 12, and the upper end of plate 10 is offset outwardly to form offset bearing 13 cooperating with bearing 12 to form a seat for the corresponding end 14 of the section 7.

Parts of the offset bearings 12 and 13 are further offset to form pour spouts 15 through which the binder 11 is adapted to be poured when the sections are assembled.

The joint between the sections 7 and 8 is substantially the same as the joint between sections 1 and 7 and the parts thereof are similarly numbered. The pour spouts 15 in the joint between sections 1 and 7 lie in the plane of section and make the joint appear slightly different from the joint between sections 7 and 8, where the pour holes are shown at an angle of 90 degrees relative to those shown in the lower joint.

It must be understood that the elements of the several sections are assembled away from the manhole excavation and that the binder 11 is poured into the space between the inner and outer plates of each section until it fills such space from the bottom of

the section up to the offsets formed to receive the lower end of the next superposed section. When an upper section is located properly on the one immediately below it, binder material can be poured in through pour holes 15 to fill the joint and integrally unite the two sections.

The sections 7 and 8, shaped as hollow truncated cones, are also made of inner and 10 outer plates 16 and 17 with the inner plate 16 arranged concentrically within the plate 17 and spaced apart therefrom to receive the binder 11.

The upper section 8 is finished flush at its 15 top edge to receive a man-hole cover 18 which may, if desired, be formed of two plates 19 and 20, separated by binder 11. As shown in the drawing, the cover 18 is provided with a flange 19' adapted to seat in a recess 21 formed in a concrete or other suitable ring, and may be removed by hooks adapted to pass through holes 22 and 23 formed in the top plate of cover 18.

The conduits 5 and 6 are also preferably 25 formed by cylindrical tubes 24 and 25 concentrically arranged and bound together by binder 11. The inner tube 24 has a flange 26 turned out to engage the inner plate 9 of the section 1 and the outer tube 25 has a 30 flange 27 formed to engage the outer plate 10 of section 1.

The whole construction is intended to provide complete insulation between the inner and outer plates of the manhole and between the inner and outer tubes of conduits connected thereto. The plates are intended to be made of rust proof iron and to be assembled in sections with binder between them before their assembly in the manhole 40 excavation.

In order to obviate the necessity of using ladders in these manholes each section is provided with a rung 28 formed by a rod of steel or other suitable material inserted 45 as a chord in slots cut in the offset 12 of the inner plate of each section.

In the modification shown in Figures 4, 5, and 6, the sections are all cylindrical, the lower section 29 being formed of concentrically spaced apart plates, 32 and 33 separated by the binder 11.

Conduits 34 and 35 similar to the conduits 5 and 6 are similarly connected to the inner and outer plates 32 and 33, respectively.

55 In order to form the joint between the sections 29 and 30, the outer plate 33 is inwardly offset at its upper end to form a recessed portion 36 and a shoulder 37 forming a seat for the outer plate 38 of the section 30. The inner plate 39 of the section 30 is spaced apart concentrically from the outer plate 38 and as usual the space between said plates is filled with binder 11. The outer plate 38 of the upper section 30 is 60 therefore flush with the outer plate 33 of the

lower section 29. The inner plate 39 of section 30 fits snugly against the outer face of the inner plate 32 of the lower section 29 and at intervals is provided with slots 40 adapted to permit binder to flow between 70 the upper and lower sections in the joint thereof when such binder is poured through the pouring offsets 41 suitably formed around the inner plate 32.

The upper section 31 is connected to the 75 adjacent lower section 30 by a similar joint and terminates at its upper end to form a seat for a concrete ring 42 in which a man-hole cover 43 similar to that shown in Figure 1 is adapted to seat. Each of the sections in this modification is provided with a rung 44 extending across the inner plates as a chord and seated in slots 45 and 46 formed in the upper edge of said inner plates, the inner plates of the upper section being 85 slotted to seat over the projecting ends of said rungs and lock them in position.

The modification shown in Figures 7 and 8 is also cylindrical and the joints between the sections 47, 48, 49 and 50 are the same 90 as are shown in Figure 1. In this modification, the lower sections 47 and 48 are provided with apertures formed to receive tubular conduits 51, 52, 53 and 54, and the inner plates of all the sections are slotted to receive the rungs 55 to form a ladder as in the previously described modifications. The manhole cover 56 is similar to that shown in Figure 1 and adapted to be similarly positioned in a concrete ring 57 seated on the top 100 of the upper section 50.

In the forms shown in Figures 9, 10 and 11, the sections are rectangularly shaped to form when suitably united a large vault or chamber from which conduits may extend 105 in any desired direction. These sections are each composed of separate units adapted to be bolted or riveted together. For example, the section 58 shown in Figure 10 is comprised of end units 59 and 60 connected by 110 flanges 61 and 62 to a central unit 63. Stiffening plates 64 (see Figure 11) are bolted or riveted to said flanges 61 and 62 near the top and bottom of said unit in order to form struts to resist the inward pressure on the 115 walls of the section.

Conduits 65 and 66 extend from the end units 58 and 60, respectively, and are composed of inner and outer tubes 67 and 68 adapted to be connected to the inner and outer walls 69 and 70 of each unit, binder 11 being poured into the spaces between spaced apart walls of said conduits and sections, as in the other modifications.

The various sections in this rectangular form of the invention are adapted to be superposed one on the other and connected by joints similar to those shown in Figure 1 of the drawing, which joints are adapted to be filled through pour holes 71 suitably 125

formed around the outer and inner plates of the lower section. Each of the sections and the units thereof may be provided with ladder rungs 72 either riveted or otherwise secured to the opposite walls of each unit or set into slots formed in the upper edges of the inner plate of each unit.

A single cover 73 may be extended over the top unit and provided with flanges adapted to facilitate the seating thereof on the top section. Where a large cover is used suitable manhole plates 74 may be formed therein in order to give admission to any part of the manhole wall without necessitating the raising of the whole cover 73. The several parts of the cover may be formed by spaced apart plates and the spaces between said plates may be filled with insulating binder 11 as desired.

It will be apparent from the foregoing description that I have provided manholes and vaults which may be varied as to size and which may be formed in sections of standard sizes adapted to be assembled very quickly and cheaply in previously formed excavations. It will also be apparent that conduits may be connected up very quickly to any of the sections forming part of the manholes described herein.

While I have shown a conduit as extending from intermediate parts of each section, it is to be understood that these conduits may be readily located at the joint between superposed sections, which may be notched to fit into each other and over any conduit positioned therebetween with the insulating binder properly packed between the element of the sections and the conduit.

What I claim is:

1. A manhole comprising a plurality of spaced apart sheet metal casings, one concentrically arranged within the other, and having bottom plates spaced apart and closing the inner and outer casings, and binding material filling the space between said bottom plates and said casings.

2. A manhole comprising a plurality of sheet metal casings spaced apart one concentrically within the other, plates closing one end of each of said casings and spaced apart from each other, a conduit extending from said casing and comprising two spaced apart concentrically arranged tubes, and an insulating binder filling the space between said plates, casing and tubes.

3. A manhole comprising a cylindrical casing having one end thereof closed, a second cylindrical casing smaller than the first casing and closed at one end and concentrically arranged in the first casing with the closed ends spaced apart, and an insulating binder filling the space between said ends and casing.

4. A manhole comprising a casing formed

of a plurality of sections joined end to end, each section comprising inner and outer plates spaced apart concentrically, one of said sections having the adjacent ends of its plates closed and spaced apart, and insulating binding material filling the space between said plates and closed ends.

5. A manhole comprising concentric inner and outer spaced apart casings having one end of each closed and spaced from the end of the other, conduits extending from said manhole each comprising an inner tube connected to the inner casing and an outer casing surrounding and spaced from the inner tube and connected to said outer casing, an insulating binder filling the space between said casings, ends, and tubes, and a cover detachably closing the open ends of said casings.

6. A manhole comprising a plurality of casings spaced apart one within the other, and closed at one end; conduits extending from said casings and comprising inner and outer tubes connected to the inner and outer casings, respectively; insulating binding material filling the spaces between said casings, ends and tubes; and rungs extending across and supported by the inner casing.

7. A manhole comprising inner and outer casings concentrically arranged one within and spaced from the other and having closed ends spaced from each other; said casings being formed of a plurality of sections superposed end to end, a ladder rung extending across each section and supported by the inner casings only, and binding material filling the space between said casings, and ends and locking said ladder rungs in each section.

8. A manhole comprising a plurality of casings concentrically arranged one within and spaced from the other, horizontal ladder rungs spaced vertically along said casing and extending through said inner casing into the space between the casings, and binding material filling the said space and engaging the ends of said rungs to lock the rungs in position.

9. A manhole comprising inner and outer casings concentrically arranged one within and spaced from the other and having closed ends spaced from each other, said casings being formed of a plurality of sections superposed end to end; a ladder rung extending across each section and supported by the inner casings only; and binding material filling the space between said casings, and ends and locking said ladder rungs in each section, said inner sections having portions of their upper edges shaped to form a spout for the admission of binding material to form the joints between said sections.

In testimony whereof I affix my signature,
JAMES D. MONIE.
